(57) **CLAIM**

The ornamental design for a sun shade extension as shown and described.

DESCRIPTION

FIG. 1 is a perspective view of a sun shade extension showing the new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the sun shade extension shown in an environment of use; and,

FIG. 11 is a back side perspective view of the sun shade extension shown in an environment of use.

The broken lines shown in FIGS. 1, 2, 3, 4 and 8 depict portions of the sun shade extension that form no part of the claimed design.

The evenly spaced broken lines in FIG. 10 and FIG. 11 depict portions of the sun shade extension that form no part of the claimed design.

1 Claim, 11 Drawing Sheets
